WELL APPARATUS

Willis A. Heath, Bartlesville, Okla., assignor to
Phillips Petroleum Company, a corporation of
Delaware

Application April 7, 1942, Serial No. 438,035

4 Claims. (Cl. 137—34)

This invention relates to well apparatus adapted to be employed in the secondary recovery of hydrocarbons, and more particularly to apparatus for controlling the flow of fluid from an upper fluid-bearing formation into a lower hydrocarbon-bearing formation through a well bore that communicates with both formations.

It has generally been the practice heretofore, in the recovery of hydrocarbons from underground formations by water flooding, to obtain the water that is transmitted into the hydrocarbon-bearing formation from either a surface or a subsurface source of supply. Whether the water is derived from a surface source of supply, such as a lake or stream, or from a subsurface source of supply, such as a water well, it is essential that suitable pumping equipment and pipe lines be provided to convey the water from the source to one or more input wells. Upon arrival at an input well the water is metered and injected therethrough under predetermined pressure. The volume and pressure of the water so introduced into the hydrocarbon-bearing formation depends on various formation characteristics which are ascertained from a complete study of the formation including analyses of core samples of the material of the formation.

In many oil pools, water-bearing formations are existent above a hydrocarbon-oil-bearing formation. Water from the upper formation may be utilized in waterflooding the hydrocarbon formation through a common well bore provided that the volume and pressure of the water is properly controlled. By employing this water it will be evident that the expense of obtaining and handling necessary water from extraneous sources can often be eliminated.

Regardless of whence the water is obtained for use in secondary recovery operations, it is important to exercise control over the pressures and volumes of the water that is injected into the hydrocarbon-bearing formation in order to effect maximum oil recovery at a minimum cost and to recover the oil within a reasonable time after operations are commenced. It is a relatively simple matter to flood a formation of uniform permeability, i. e., one in which the resistance to flow of fluid is substantially the same throughout. Unfortunately, such is rarely the case, as the permeability of individual oil reservoirs varies widely and fluids urged therethrough flow along the path of least resistance which is through the more permeable regions. Care must

therefore be taken to move the oil content through the formation in a body. If the quantity and pressure of the water that is injected into the formation is excessive, it will break through or by-pass the oil "bank" and flow toward the output well with the result that only small portions of oil, if any, will be recovered per unit time. On the other hand, should only small amounts of water be injected into the formation, it may be months or even years before any appreciable quantity of oil is recovered. From the foregoing, it will be evident that small volumes of injected water at low pressure or large volumes at excessive pressure are each undesirable from an economic point of view. It is therefore essential that the fluid driving medium, generally water, must be introduced into the formation in proper quantities and under proper pressures.

20 The present invention provides apparatus which permits the passage of controlled quantities of water from an upper formation into a lower hydrocarbon-bearing formation to thereby achieve effective and economical hydrocarbon oil recovery by water flooding through a common cased well bore which is perforated at the region of the water bearing formation. The well casing is packed off at a point intermediate the formations and a conduit extends through the packing. Said conduit includes a lower portion which is relatively stationary in the well bore and an upper portion that is telescopically disposed with respect to the lower portion. A plurality of spaced passages in the lower portion of the conduit may be placed in or out of communication with an annular space formed between the conduit and the casing by raising or lowering the upper portion of the conduit. As will be apparent from the detailed description set forth further along, the injection of water into the hydrocarbon-bearing formation is at all times under the control of the operator.

45 This invention therefore has for its principal object the provision of apparatus for transmitting controlled quantities of fluid from an upper fluid-bearing formation into a lower fluid-bearing formation through a common well bore to drive the fluid in the lower formation toward a region whence it is withdrawn to the surface of the ground.

It is another object of this invention to provide apparatus for effectively and economically flooding an underground reservoir.

A further object of this invention is to provide apparatus of the character indicated, which

apparatus is sturdy and simple in construction and comparatively inexpensive to manufacture, install and operate.

These and other objects and advantages will be apparent to persons skilled in the art by reference to the following description and annexed drawing which respectively describe and illustrate a preferred embodiment of the invention, and wherein

Figure 1 is an elevation view of the apparatus of the invention disposed in a well bore and positioned in perforate well casing that is shown in central longitudinal cross section; and

Figure 2 is an enlarged view of a portion of the apparatus shown in Figure 1, partly in cross section.

Referring to the drawing, and more particularly to Figure 1 thereof, I have denoted a well bore 10 that extends through a water-bearing formation 11 and that penetrates a hydrocarbon oil-bearing formation 12. A string of well casing 13 extends downwardly through the well bore and is provided with a plurality of perforations 14 in the region of water formation 11 to permit the entrance of water thereto. A string of tubing 15 is disposed within casing 13 and spaced therefrom to form an annular passage 16. Tubing string 15 is coupled to a control apparatus, generally indicated by reference numeral 17; communicates with a conduit 18 that extends through a conventional packer 19, such as a hook wall type of packer; and terminates in a tail pipe 20. It will be noted that by virtue of the arrangement illustrated in Figure 1, packer 19, when in operative position, prevents water admitted into annular passes 16 from flowing therethrough into the lower formation; but permits fluid introduced into tubing string 15 to pass directly into said lower formation.

Let us turn next to Figure 2 for details of construction of the equipment generally referred to by numeral 17. It will be observed that a swaged body 21 is secured to tubing 15 by means of a connector 22. The lower portion of body 21 is bored on several diameters and is telescopically arranged with respect to conduit 18 which carries a ring flange 23 at its upper end and is provided with a plurality of peripherally spaced ribs 24 that are adapted to be received in corresponding grooves 25 in the body. A gasket or packer 26 is maintained in the illustrated position by means of a follower sleeve 27 that is in threaded engagement with the lower extremity of swaged body 21. Gasket 26 forms an adequate seal to prevent the leakage of fluid between body 21 and the outer surface of conduit 18. A series of vertically spaced ducts 28 is provided in conduit 18 to establish communication between the interior of the conduit and annular passage 16 under conditions which will be explained in the discussion of the operation of the invention. A body 29 embraces conduit 18 and supports a ring 30 that is composed of rubber or a similar material and that is adapted to form a seat to receive end face 31 of sleeve 27.

In the practice of my instant invention, the apparatus is assembled and lowered into a well bore until it assumes the position illustrated in Figure 1 with packer 19 expanded to bridge annular passage 16 and support conduit 18 and the equipment therebelow in a substantially fixed position. It will be noted that with the apparatus disposed in this manner, packer 19 is located at a level intermediate perforations 14 in casing 13 and oil-bearing formation 12. It will

be noted further that swaged body 21 has been lowered with respect to conduit 18 until sleeve 27 engages ring 30 to form an effective fluid seal therewith. Water enters casing 13 from water-bearing formation 11 by way of perforations 14.

Tubing 15 is raised a sufficient distance to unseat follower sleeve 27 from ring 30 and to establish communication between lowermost duct 28 and annular passage 16 whereupon water in the annular passage flows through said duct and downwardly into oil formation 12. The head of water in the tubing string and the rate of flow of the water into formation 12 may be readily determined in any manner well known in the art. The rate of flow and the pressure of the water thus transmitted from water formation 11 into oil formation 12 is determined for various relative positions of body 21 and conduit 18. It will be obvious that the greater the number of ducts 28 that are placed in direct communication with annular passage 16, the greater will be the quantity of water and hence the pressure of the column of water in the apparatus. For example, when tubing 15 and body 21 is raised to the position illustrated in Figure 2, it will be seen that the three lowermost ducts 28 communicate directly with annular passage 16, thereby allowing more water to enter conduit 18 than if only the lowermost or the two lowermost ducts communicated directly with passage 16. By the same token, correspondingly greater quantities of water will flow into conduit 18 when the tubing string is raised so as to expose additional ducts.

Having previously studied the characteristics of oil-bearing formation 12 and having ascertained the quantity and pressure of the water necessary to obtain optimum results in the secondary recovery operations, tubing 15 is raised until the requisite number of ducts 28 are placed in direct communication with annular passage 16. The transmission of water into the tubing string may be varied at will by adjusting the relative position of body 21 and member 29. When it is desired to terminate flow into conduit 18, tubing 15 is lowered until gasket 26 seals conduit 18 below the lowermost duct, or preferably until follower sleeve 27 is firmly seated on ring 30. To remove the apparatus from well bore, tubing 15 is raised until grooves 25 in body 21 engage ribs 24. The tubing is then turned about a vertical axis, thereby turning conduit 18 and disengaging packer 19 from the interior wall of the well casing. With the packer thus freed, the entire mechanism is withdrawn from the well bore in the usual manner.

From the foregoing, it is believed that the operation and advantages of the apparatus for practicing my instant invention will be readily comprehended by persons skilled in the art. It is to be clearly understood, however, that various changes in the apparatus shown and described may be resorted to without departing from the spirit of the invention, as defined by the appended claims.

I claim:

1. In apparatus of the character described, the combination comprising an outer conduit, an inner conduit extending into and spaced from the outer conduit to form an annular passage therewith, one of the conduits being longitudinally movable with respect to the other conduit, means comprising a flexible member carried by one of the conduits for forming a fluid seal across the annular passage, a combined stop and valve mem-

ber carried by the inner conduit for limiting longitudinal movement of the movable conduit with respect to the other conduit in one direction and for cooperating with one end of the outer conduit to form a fluid seal between the annular passage and the exterior of the outer conduit, means for effecting coupling engagement between the conduits upon predetermined longitudinal movement of the movable conduit in the opposite direction to limit relative movement of the movable conduit with respect to the other conduit in said opposite direction and to prevent relative rotational movement of either conduit with respect to the other conduit while permitting relative longitudinal movement of the movable conduit with respect to the other conduit in the first mentioned direction, and a plurality of longitudinally spaced ports in the inner conduit, one of said ports establishing communication between the interior of the inner conduit and the exterior of the outer conduit upon predetermined longitudinal movement of the movable conduit in one direction, additional ports coacting with the flexible member and establishing communication between the interior of the inner conduit and the exterior of the outer conduit upon further predetermined longitudinal movement of the movable conduit in the same direction.

2. The combination in accordance with claim 1 wherein the first mentioned means comprises a flexible member secured to the movable conduit and disposed intermediate the extreme ends thereof.

3. The combination in accordance with claim 1 wherein the second mentioned means comprises at least one projection extending beyond the outer surface of the inner conduit and at least one groove formed in the inner surface of the outer conduit to receive said projection.

4. In apparatus of the character described, the combination comprising an inner conduit, an out-

er conduit surrounding a portion of the inner conduit and spaced therefrom to form an annular passage therewith, said outer conduit being movable longitudinally with respect to the inner conduit, a flexible member secured to and movable with the outer conduit and disposed intermediate the extreme ends of the outer conduit to form a fluid seal across the annular passage, a combined stop and valve member carried by the inner conduit for limiting longitudinal movement of the outer conduit with respect to the inner conduit in one direction and for cooperating with one end of the outer conduit to form a fluid seal between the annular passage and the exterior of the outer conduit, means for effecting coupling engagement between the conduits upon predetermined movement of the outer conduit in the opposite direction to limit relative movement of the outer conduit with respect to the inner conduit in said opposite direction and to prevent relative rotational movement of either conduit with respect to the other conduit while permitting relative longitudinal movement of the outer conduit with respect to the inner conduit in the first mentioned direction, said means including at least one projection extending beyond the outer surface of the inner conduit and at least one groove formed in the inner surface of the outer conduit to receive said projection, and a plurality of longitudinally spaced ports in the inner conduit, one of said ports establishing communication between the interior of the inner conduit and the exterior of the outer conduit upon predetermined longitudinal movement of the outer conduit in one direction, additional ports establishing communication between the interior of the inner conduit and the exterior of the outer conduit upon further predetermined movement of the outer conduit in the same direction.
